CLIP APPLYING DEVICE

Arthur D. Park and Milton G. Brown, Lancaster,
Pa., assignors to Armstrong Cork Company,
Lancaster, Pa., a corporation of Pennsylvania

Application September 23, 1939, Serial No. 296,170

6 Claims. (Cl. 1—47)

Our invention relates to clip holding devices, and more particularly to a device adapted to hold a clip in predetermined position while it is being secured in a wallboard assembly and to secure such clip in fixed position in the assembly. The term "wallboard assembly" is used herein by way of definition and not of limitation, it being intended to include within its scope, wallboard, plasterboard, corkboard, or fiberboard in the form of tiles, blocks or slabs used for insulating or acoustical purposes in building structures.

Heretofore, wallboard assemblies have been generally erected by driving nails or similar fastening means through the boards and studding forming a supporting structure. Such procedure possesses many disadvantages, among which are the low rate of assembly, the careful handling of the wallboards required even from skilled labor, the necessity of replacing boards tearing away from the fastening means, and the additional expense involved in such measures. In order to eliminate such disadvantages, it has been proposed to erect wallboard assemblies by the use of wallboard clips such, for example, as shown in Stubbs Patent No. 2,008,192, granted July 16, 1935; Tummins Patent No. 2,174,145, granted September 26, 1939; and Tummins patent application, Serial No. 279,381, filed June 16, 1939. The use of wallboard clips eliminates face nailing, obviates the necessity of replacing wallboards which have torn away from fastening means, and has speeded up the rate of assembly to some extent. It has not speeded up the rate of assembly to any great extent due to the difficulties involved in the use of such clips; that is, when a clip is used it is necessary to hold it securely in place by hand, to hold the wallboard in place, to hold clip fastening means, such as nails or brads, in position, and to drive such fastening means into the supporting studding, all at the same time.

Our invention has for its chief object to provide a device adapted to hold a clip in predetermined position while it is being secured in a wallboard assembly and to secure such clip in fixed position in the assembly. An object of our invention is to provide an economical device for such purposes which can be readily and satisfactorily used by unskilled labor. A further object is to provide a device which considerably decreases time required in assembling wallboard structures, eliminates a large portion of the labor cost involved in such structures, and permits a more attractive installation to be obtained at less cost than heretofore deemed possible.

Our invention relates to a device adapted to hold a clip in predetermined position while it is being secured in a wallboard assembly and to secure such clip in fixed position in the assembly, which comprises a body portion having a nail re-

ceiving recess, clip retaining means placed in predetermined relationship to said body portion, and means adapted to force a nail placed in the recess through a held clip and into the assembly thereby securing the clip in fixed position therein.

Our invention further relates to a clip supporting element for use in a device adapted to hold a clip in predetermined position while it is being secured in a wallboard assembly and to secure such clip in fixed position in the assembly, which comprises a magnetized block having a planar seat adapted to receive a clip, the sides of the block having openings therein adapted to receive a projection or projections on the clip, and means for securing the block to said device.

The attached drawing illustrates a preferred embodiment of our invention, in which,

Figure 1 is a sectional view taken longitudinally through our device, serving to illustrate the construction thereof;

Figure 2 is an isometrical view of our device illustrating the manner in which a clip is held for erection in an assembly, the clip being shown in dotted outline; and

Figure 3 is an isometrical view of a clip usable with our device.

Referring to the drawing, there is shown a hollow tubular body 2 provided at one end with a nail receiving recess or socket 3. Preferably, the exterior of the hollow tubular body 2 is knurled to assist the user in readily holding the device. The opposite end of the tubular body 2 is provided interiorly with a thread 4, for a purpose hereinafter explained. Immediately above the nail receiving recess or socket 3, the wall of the body 2 projects inwardly to form a seat 5 for a spring 6. A punch 7 is fitted within the body 2, the punch 7 consisting of a solid rod, the end 8 thereof forming the base of the nail receiving recess 3. The punch 7 is adapted to move axially to eject a nail or brad from the recess 3. A collar 9 is welded to the punch 7.

The helical spring 6 rests on the seat or projecting portion 5 of the body 2 in spaced relationship to the punch 7 and is held between the collar 9 and the seat 5. The spring 6 is adapted to retract the punch 7 to its original position after axial movement thereof to eject a nail from the recess 3. A locking element is provided to securely hold the punch 7 within the body 2, such element consisting of a knurled finger portion 10 having a depending spindle 11 provided with an exterior thread 12, the thread 12 of the spindle 11 being adapted to engage the thread 4 of the body 2 to lock the punch 7 within the body 2 and to prevent its removal therefrom. Upon attempted removal of the punch 7 from the body 2, the collar 9 engages the spindle 11 thus preventing its removal.

A clip retaining element is provided to securely hold a clip in predetermined position while it is being secured in a wallboard assembly. The clip retaining element comprises a magnetized block 13, adapted to fit securely on the body 2 surrounding the nail receiving recess or socket 3. A set screw 14 is used to hold the block 13 to the body 2. At least the face 15 of the block 13 is magnetized to magnetically attract a metal clip, the face 15 forming a seat for such clip. The face 15 is formed in two sections so as to increase its magnetic force. The groove 16 separating the face 15 in two sections extends across the face and to a substantial depth within the block. The groove 16 provides openings 17 in opposite side surfaces of the block 13 adapted to receive the projection of a clip; the junctures between the walls of the groove 16 and the opposite side surfaces of the block 13 are beveled or tapered as shown at 18 so as to provide a V-shaped formation of the ends of the groove, thus assisting in guiding the projection or point of a clip within the groove. Preferably, the face 15 of the block 13 is beveled at a slight angle to aid in the assembling operation since the normal position of the device in use is at a slight angle.

In using the device, a nail is placed within the socket 3, and a clip 19 seated on the face 15 of the block 13, the point of the nail passing through an opening in the clip, as shown in Figure 2, and the projection 20 of the clip penetrating the opening 17 in the side surface of the block 13. The device is placed adjacent an assembly and holds the clip in predetermined position therein, the end 21 of the clip 19 fitting within a groove in the edge of the wallboard. A hammer is used to strike the end of the punch 7 to eject a nail placed in the socket 3 and to force the nail in the supporting studding thereby securely holding the clip in fixed position in the assembly and holding the wallboard to the supporting studding. The device is then removed and a second wallboard placed in the assembly, the point 20 of the clip 19 being forced therein, and the device used in the manner above described to fasten the board on its opposite edge. As many clips may be used to secure the wallboard in position as desired.

The advantages involved in the use of our device are obvious. The finished structure presents a more attractive appearance. The assembling operation is speeded considerably and the labor cost involved in such operation is decreased. The device may be manufactured economically and can be readily used by unskilled labor.

While we have described and illustrated a preferred embodiment of our invention, it will be understood our invention is not so limited since it may be otherwise embodied within the scope of the following claims.

We claim:

1. A device adapted to hold a clip in predetermined position while it is being secured in a wallboard assembly and to secure such clip in fixed position in the assembly, comprising a hollow body, a portion of said body being adapted to receive a nail, brad or similar fastening means, magnetized clip supporting means placed adjacent the nail receiving portion of said body, a punch adapted to move axially of said body to

force a nail through a held clip and into the assembly thereby securing the clip in fixed position in the assembly, and means to retract said punch to its original position.

2. A device adapted to hold a clip in predetermined position while it is being secured in a wallboard assembly and to secure such clip in fixed position in the assembly, comprising a body portion having a nail receiving recess, a magnetized block surrounding the nail receiving portion of said body adapted to hold a clip in predetermined position, and means adapted to force a nail placed in the recess through a held clip and into the assembly thereby securing the clip in fixed position therein.

3. A device adapted to hold a clip in predetermined position while it is being secured in a wallboard assembly and to secure such clip in fixed position in the assembly, comprising a tubular body, a portion of said body being adapted to receive a nail, brad, or similar fastening means, a magnetized block surrounding the nail receiving portion of said body, said block being adapted to hold a clip in predetermined position for erection in the assembly, a punch adapted to move axially of said body to force a nail through a held clip and into the assembly thereby securing the clip in fixed position in the assembly, and means to retract said punch to its original position.

4. A device adapted to hold a clip in predetermined position while it is being secured in a wallboard assembly and to secure such clip in fixed position in the assembly, comprising a hollow tubular body, one end of said body forming a nail receiving socket, a punch fitted in said body and adapted for movement axially thereof, an end of said punch forming the base of the nail receiving socket, means adapted to prevent removal of said punch from said body, a magnetized block surrounding said nail receiving socket adapted to hold a clip in predetermined position for erection in the assembly, and a spring fitted in said body in predetermined spaced relationship to said punch, said spring being adapted to retract said punch to its original position after axial movement thereof.

5. A clip supporting element for use in a device adapted to hold a clip in predetermined position while it is being secured in a wallboard assembly and to secure such clip in fixed position in the assembly, comprising a magnetized block, the face surface of said block forming a seat for a clip and having a groove therein extending to a substantial depth within said block, the juncture between the walls of the groove and opposite side surfaces of the block being beveled, and means for securing said block to said device.

6. A device adapted to hold a clip in predetermined position while it is being secured in a wallboard assembly and to secure such clip in fixed position in the assembly, comprising a body portion, a magnetized block surrounding said body portion adapted to support a clip in predetermined position in the assembly, and means for securing a supported clip in the assembly, said means including a punch adapted to force a nail through a supported clip and into the assembly.

CERTIFICATE OF CORRECTION.

Patent No. 2,258,861.

October 14, 1941.

ARTHUR D. PARK, ET AL.

It is hereby certified that error appears in the printed specification of the above numbered patent requiring correction as follows: Page 2, second column, line 45, claim 4, strike out the word -- spaced --; and that the said Letters Patent should be read with this correction therein that the same may conform to the record of the case in the Patent Office.

Signed and sealed this 9th day of December, A. D. 1941.

Henry Van Arsdale,
Acting Commissioner of Patents.
